(57) **CLAIM**

The ornamental design for a connector for stair tread measuring device, as shown and described.

DESCRIPTION

FIG. 1 is a first perspective view of a connector for stair tread measuring device, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a second perspective view showing the connector for stair tread measuring device, in state of use; and,

FIG. 9 is a third perspective view showing the connector for stair tread measuring device, in another state of use.

All the broken lines in the drawings depict portions of the connector for stair tread measuring device that form no part of the claimed design.
